TUBING ADAPTOR FOR INTERCOUPLING BETWEEN PASSAGEWAYS OF DIFFERENT DIAMETER PRIMARILY IN MEDICAL, SURGICAL AND VETERINARY APPLICATIONS

James Bernard Willmott, 195 Burmarsh Road, Hythe, England, and Andrew Gordon Hanton, 63 Grasmere Gardens, Folkestone, England

Filed Sept. 17, 1973, Ser. No. 398,057

Claims priority, application Great Britain Mar. 16, 1973

Term of patent 14 years

Int. Cl. D24—99, D23—01
U.S. Cl. D83—1 R

FIG.1.

FIG.2.

FIG.3.

FIG.4.

FIG.5.

FIG. 6.

FIG. 7.

FIG. 8.

FIG. 9.

FIG. 10.

FIG. 1 is a perspective view from below of a first embodiment of the tubing adaptor for intercoupling between passageways of different diameter primarily in medical, surgical, and veterinary applications, showing our design;

FIG. 2 is a top plan view of the adaptor of FIG. 1;

FIG. 3 is a side elevation of the adaptor of FIG. 1;

FIG. 4 is an end elevation of the adaptor of FIG. 1;

FIG. 5 is a section taken on line 5-5 of FIG. 4;

FIG. 6 is a perspective view from below of a second embodiment of the tubing adaptor showing our design;

FIG. 7 is a top plan view of the adaptor of FIG. 6;

FIG. 8 is a side elevation of the adaptor of FIG. 6;

FIG. 9 is an end elevation of the adaptor of FIG. 6; and

FIG. 10 is a section taken on line 10-10 of FIG. 9.

We claim:

The ornamental design for a tubing adaptor for intercoupling between passageways of different diameter primarily in medical, surgical and veterinary applications, substantially as shown and described.
